APPLYING AND REMOVING DEVICE

James A. Jensen, Philadelphia, Pa., assignor to Charles E. Frick, Jr., J. Rodman McCoy, Elsie T. Heller, John H. Jensen, and James A. Jensen, copartners, trading under name of Philadelphia Valve Company, Philadelphia, Pa.

Application February 3, 1940, Serial No. 317,058

6 Claims. (Cl. 29—84)

This invention has reference to devices or tools for placing and removing articles normally out of manual reach and, more particularly, to implements designed for grasping an article to be placed or removed. Preferably, the present improvements relate to devices or tools of the wrench type usable for removing and replacing the operative parts of vehicle tank emergency valves whenever desirable or expedient.

The fundamental object of this invention is to provide an applying and removing device that will, for convenience, be hereinafter generally termed a "jack-wrench," serve for lifting and replacing the bonnet and associated parts of vehicle tank emergency valves irrespective of the location of said valves with respect to the tank manhole, and without any necessity of the operator entering the vehicle tank.

Another object is to provide a jack-wrench, as indicated in the preceding paragraph, which is capable of grasping the valve part or parts to be removed from any reasonable angle with pre-assurance of being disconnected and assembled with ease.

A further object is to provide a jack-wrench for the above indicated purposes which is simple in construction and easy to operate at a distance from the article to be removed or replaced; and which is made of a material that will not "spark" when knocked against the tank inner wall, whereby the hazards of fire and explosion are eliminated.

Other objects, with ancillary advantages, achieved by this invention will be apparent from or specifically referred to in the following detailed description of a typical embodiment, as illustrated by the accompanying sheets of drawings, while the features of novelty are more definitely expressed in the concluding claims.

In the drawings:

Fig. 1 is a fragmentary longitudinal section of one end of a tank truck showing the improved jack-wrench of this invention in position ready for manipulation to effect release and removal of an emergency valve bonnet and associated parts.

Fig. 2 is a fragmentary vertical section through the emergency valve upper part and bonnet with a broken portion of the jack-wrench of this invention engaged with the valve stem and bonnet top ready for actuation to remove said bonnet and associated valve parts.

Fig. 3 is a similar vertical section showing the respective parts in a different position, or with the valve and bonnet raised ready for withdrawal

from the emergency valve body and lifting out of the tank.

Fig. 4 is a broken, part elevation and part sectional view of the jack-wrench of this invention in a preferred form.

Fig. 5 is a plan section, taken as indicated by the arrows V—V in the preceding view.

Fig. 6, Sheet 1, is an elevation of the lower and wrench portion, taken as indicated by the arrows VI—VI in Fig. 4.

Fig. 7, Sheet 1, is a perspective view of a fork component included in the jack-wrench, the same being hereinafter more fully described; and,

Fig. 8, Sheet 1, is a perspective view of a jaw component likewise later on explained in detail.

In the following detailed description of the preferred embodiment of this invention illustrated by the accompanying three sheets of drawings, specific terms will be employed for the sake of clarity, but it is to be understood that such terms are used in a descriptive sense only and not for purposes of limitation. Each specific term is intended to include all technical equivalents capable of serving in a similar capacity to accomplish an analogous purpose.

Referring to the drawings with greater particularity, the jack-wrench of this invention comprises a manipulator portion comprehensively designated 1, with an operatively coordinated grasp means similarly designated as 2. The manipulator portion 1 comprises a length of tubing or body portion 3 having one end screw-threaded at 4 for rigid attachment of a fork 5 with a plain bore section 6. At a predetermined distance from the other end of the body portion 3 is permanently secured as by welding 7 a radially-related handle 8; while the proximate end of said body portion is fitted with a rotatable cap-bushing 9. The cap-bushing 9 is provided with a bore 10 for snug passage of a shaft 11, embodying a crank 12 for purposes of rotation, and said bushing is firmly clamped on the shaft 11, by a set screw 13, at the requisite position to accommodate joint rotation of the shaft 11 and cap-bushing 9.

The inner end of the shaft 11 is preferably screw-threaded at 14 for attachment thereto of the one component 15 of a conventional ball universal joint 16, the other component 17 of said joint serving as the coupler with the actuator member 18 for the grasp or wrench means 2, hereinbefore referred to; while a drift pin 19 effectively prevents relative rotation of the parts 14 and 15 after assembly.

The wrench means 2 comprise a yoke member or head 20 embodying spaced coupler portions 21 braced by fillets 22, said coupler portions being provided with aligned apertures 23 for the passage of pivot studs 24, whereby the head 20 is fulcrumed to the corresponding coupler portions 25 of the fork 5, hereinbefore referred to. In order that the parts 21 and 25 may be retained in frictional engagement, with capacity for relative movement, the pivot studs 24 are fitted with castellated nuts 26 and spring washers 27. The head 20 is provided with spaced bores 28, 29, through the former of which passes the plain section 30 of the lifting-screw portion 31 of the actuator 18, with the adjoining end reduced and screw-threaded at 32 for engagement in the correspondingly threaded bore 33 of the universal-joint component 17, and to which it is fixedly connected by a drift-pin 34. Rigidly secured in the bore 29 of the head 20, in parallel with the actuator 18, as by a nut 35 and lock washer 36 is the one reduced end 37 of a guide member 38, the other reduced end 39 whereof is similarly clamped through a bore 40 in the stationary jaw 41 of the grasp means 2. The stationary jaw 41 and movable jaw 42 of the grasp means 2 are substantially complementary with the exception that the former is provided with a second plain bore 43 through which the reduced end 44 of the lifting screw 31 is passed, and clamped thereto by a castellated nut 45 and lock washer 46. On the other hand, the movable jaw 42 is provided with a threaded bore 47 for coaction with the actuator screw-thread section 31 as well as a plain bore 48 for sliding coaction with the guide member 38, whereby said member is retained in registration with the stationary jaw 41 in an obvious manner; while a spacing washer 49 prevents the jaws being brought into arrestive engagement. Each jaw 41, 42 is formed with a fork portion 50 and a concaved face 51 for purposes hereafter set forth.

Having described the improved jack-wrench of this invention, the manner of using and operating the same for removing and replacing will now be set forth, by way of example, in connection with an emergency valve 52, Fig. 1, located in the bottom of a vehicle tank 53 having an access opening or manhole 54. The valve 52 includes a removable bonnet 55 provided with circumferentially spaced latch devices 56 engageable in an annular groove 57 within the valve 52, said latch devices having counterweighting heel portions 58 for coaction with the valve 52; the stem 59 whereof extends upwardly through the bonnet 55 and has a suitable bail-head 60 at its top. In practice the user of the jack-wrench inserts the same through the manhole 54 until the grasp means 2 occupies the approximate position shown in Fig. 1, with the jaws 41, 42 closed as illustrated in Figs. 1 and 4, whereupon the operator moves the jack-wrench jaw fork portions 50 into engagement with the valve stem 59, with the stationary jaw concavity 51 seating on top of the bonnet 55, as shown in Fig. 2, and it will be seen that the grasp means 2 is thereby readily positioned and steadied against lateral movements tending to displacement. The user next grasps the handle 8 firmly in one hand and turns the crank 12 with the other, with resultant rotation of the shaft 11 and actuator 18, which by means of its screw portion 31 elevates the movable jaw 42 until the concavity 51 of the latter engages below the valve spindle head 60. Con-

tinued turning of the crank 12 gradually raises the stem 59 and with it the valve member 61 above the normal "lift" of the latter, or until said valve engages the heels 58 which rocks the latter on their pivots 62 radially inwards and thereby releases the bonnet 55 in an obvious manner, as clearly understandable from Fig. 3. The operator can now easily withdraw the bonnet 55 and valve member 61 through the manhole 54 for repair or refacing of said valve member and, by a reversal of the operation just described, readily replace said parts, with consequent secure reattachment of said bonnet to the valve 52 by automatic snap re-engagement of the latch devices 56 in the groove 57.

From the foregoing it will be appreciated that the invention disclosed fully justifies the objects and advantages set forth in the prefatory paragraphs of this specification. It will also be apparent that while a preferred form of the invention has been described for a specific purpose, that said invention is capable of modification and other applications; accordingly the right is hereby reserved to all such changes and modifications reasonably coming within the scope of the following claims and the prior art permits.

Having thus described my invention, I claim:

1. In an applying and removing device, a tubular manipulator having a rigid fork at one end and a rotatable cap-bushing at the other; a wrench device including a yoke pivotally connected to the manipulator fork, a stationary jaw, a movable jaw and a coactive screw intermediate the stationary jaw and the yoke, said screw having journaled connection with the yoke and stationary jaw and the movable jaw threaded thereon for movement between said yoke and jaw, a coaxial shaft in the manipulator projecting beyond the fork and cap-bushing with rigid connection to the latter; a universal coupling between the proximate ends of said shaft and the wrench device screw; means whereby the manipulator is held stationary; and means for rotating the coaxial shaft to effect opening and closure of the wrench device jaws.

2. In an applying and removing device, a tubular manipulator having a rigid fork at one end and a rotatable cap-bushing at the other; a wrench device including a yoke pivotally connected to the manipulator fork, a stationary jaw, a movable jaw and a coactive screw intermediate the stationary jaw and the yoke, said screw having one end journaled in the yoke with the other end journaled in the stationary jaw, said movable jaw being threaded on said screw for movement between the stationary jaw and the yoke, a guide member rigidly spacing the yoke and stationary jaw with means confining the movable jaw to reciprocal movement; a coaxial shaft extending through the manipulator and projecting past the fork and cap-bushing with rigid connection to the latter; a universal coupling between the proximate ends of said shaft and the wrench device screw; means whereby the manipulator is held stationary; and means for rotating the coaxial shaft to effect opening and closure of the wrench device jaws.

3. The combination of claim 2, wherein the stationary and movable wrench jaws are provided with fork portions, and said portions have counter-related concave faces.

4. The combination of claim 2, wherein the pivotal connection between the manipulator fork and the wrench device yoke includes adjustable

spring elements for imposition of frictional engagement between the said yokes, and the universal coupling is of the ball-joint type.

5. The combination of claim 2, wherein the manipulator is provided with a rigid grasp handle, and the coaxial shaft has a crank extension for rotative purposes.

6. The combination of claim 2, wherein the movable jaw actuating screw is reduced at one end for rotary support by the stationary jaw, and a washer on said reduced end serves to prevent frictional binding of the jaws when closed.

JAMES A. JENSEN.
